UNITED STATES PATENT OFFICE.

WILLIAM THOMAS WOOD, OF NASHVILLE, TENNESSEE.

VAPOR-LAMP.

No. 888,679.

Specification of Letters Patent.

Patented May 26, 1908.

Application filed December 29, 1906. Serial No. 350,003.

To all whom it may concern:

Be it known that I, WILLIAM THOMAS WOOD, a citizen of the United States, residing at Nashville, in the county of Davidson and State of Tennessee, have invented a new and useful Vapor-Lamp, of which the following is a specification.

This invention relates to that part of lamps wherein liquid fuel is converted into vapor, which in turn is mixed with air and afterwards burned to cause the incandescence of a mantle.

The principal object in the present invention is to produce a novel structure, which is not only very efficient in operation, but is exceedingly simple in construction, so that it can be manufactured at small cost.

The preferred embodiment of the invention is illustrated in the accompanying drawings, wherein:—

Figure 1 is a vertical sectional view through the lamp. Fig. 2 is a front elevation thereof. Fig. 3 is a sectional view on the line 3—3 of Fig. 1. Fig. 4 is a sectional view on an enlarged scale on the line 4—4 of Fig. 3.

Similar reference numerals designate corresponding parts in all the figures of the drawing.

In the form of construction illustrated, a one-piece support is employed, consisting of a vertically disposed valve casing 5 from an intermediate portion of which extends a horizontally disposed starting cup 6, having on diametrically opposite sides offset ears 7. A fuel conducting channel or conduit 8 extends through the interior of the valve casing, and is supplied from any suitable source through the medium of a pipe 9. The channel 8 includes a vertically disposed portion 10 surrounding a valve seat 11 and co-operating with the seat is a needle valve 12 threaded into the casing through its lower end and preferably surrounded by a suitable stuffing box 13.

Secured to the ears 7 of the starting cup is a mixing and burner element comprising an upstanding mixing chamber 14 and spaced upstanding burners 15, communicating at their lower ends with the lower end of the chamber, as shown at 16. The burners 15 have perforate caps 17 and are disposed on opposite sides of the mixing chamber and between the same and the supply pipe 9. The mixing chamber is supplied with air through conduits 18, communicating with the upper end of the said chamber and extending exte-

riorly and downwardly on opposite sides of the chamber, their lower inlet ends being open, as shown at 19, and being disposed below the horizontal plane of the upper ends of the burners 15. These conduits constitute what may be termed a dome or hood that extends on opposite sides of and over the upper open end of the tube 14, as shown in Fig. 3.

A vaporizing tube connects the upper end of the valve casing 5 and the upper end of the mixing chamber. One end of the said tube is threaded, as shown at 20, into the upper end of the casing 5 and is surrounded by a stuffing box 21. From this end, the tube extends vertically, as shown at 22, and has its upper portion arranged in overhanging relation, as illustrated at 23. From the overhanging portion 23 to the mixing chamber, the tube is formed with a serpentine curve 75 that produces a series of opposite elongated vertically disposed loops 24 and 25, the loops 24 extending at an inclination downwardly toward the vertical portion 20, the outstanding loops 25 extending upwardly. The various loops and the vertical portions 22 are arranged in substantially the same vertical plane, which plane passes between the burners 15 and bisects the mixing chamber 14. This it is thought will be clear by reference to Fig. 2.

The discharge end 26 of the vaporizing tube is located directly over the upper end of the mixing chamber to which it is fastened by a clamp bracket 27. The said end terminates above the chamber, the latter, or hood, having an inlet orifice 28 in line therewith. A tip 29 is slidably fitted in the discharge end of the tube and has its inner portion provided with a downwardly tapered opening 30, terminating in an orifice 31 that is in register with the orifice 28. A stem 32 having its lower end secured to a depending lug 33 on the mixing chamber has its upper end connected to the tip 29 to hold the same in place. The lower portion 34 of the stem 32 is looped in order to permit a yielding movement thereof.

In the operation of the device a preliminary heating of the burner is effected by means of suitable material placed in the cup 6, as is well known to those skilled in the art. The passage of fuel supplied through the pipe 9 is controlled by the valve 12, and that which passes into the vaporizing tube will successively enter the various loops. The lower ends of the inwardly extending loops

constitute traps in which the liquid will be maintained until vaporized, and their particular disposition is important. By having them one below the other, each is subjected 5 to the fullest degree of heat from both of the opposite burners, and one will not interfere with the passage of the heat to the other. Moreover by the arrangement as disclosed, the liquid first enters the uppermost loop or 10 trap, and if any passes the same, it will gravitate to the next and so on through the others. These traps are located different distances above the burners and are therefore subjected to different degrees of heat, and as a result, 15 the complete vaporization of the liquid is insured. Vapor passing through the tip 29 will be injected into the mixing chamber 15. Here it will intermingle with the air supplied through the conduits 18, and the mixture will 20 pass through the burners 15. It will be evident that the structure is very simple, so that it can be readily and cheaply manufactured, and it is furthermore entirely effective, insuring the complete vaporization of fuel before 25 the same reaches the mixing chamber.

From the foregoing, it is thought that the construction, operation, and many advantages of the herein described invention will be apparent to those skilled in the art, without further description, and it will be understood that various changes in the size, shape, proportion, and minor details of construction, may be resorted to without departing from the spirit or sacrificing any of the advantages 35 of the invention.

Having thus fully described my invention, what I claim as new, and desire to secure by Letters Patent, is:—

1. In a vapor lamp, the combination with 40 a single piece support comprising a supply conduit, a valve casing and a starting cup having spaced ears, of a mixing and burner element secured to the ears and located over but spaced from the cup, a vaporizer connected to the valve casing and to the mixing and burner element, and a controlling valve 45 operating in the valve casing.

2. In a vapor lamp, the combination with a burner, of a vaporizing tube associated 50 therewith and formed with a serpentine curve that produces a plurality of reversely curved elongated loops disposed one below the other within the range of heat from the burner and at different distances therefrom.

55 3. In a vapor lamp, the combination with a burner, of a vaporizing tube located at one side of the burner and formed with a serpentine curve that produces a plurality of substantially vertical loops arranged one below 60 the other at different distances from the burner.

4. In a vapor lamp, the combination with a burner, of a vaporizing tube located in a vertical plane at one side of the burner, said 65 tube having an overhanging upper portion,

and an elongated substantially vertical loop arranged beneath the overhanging portion, the inner end of said loop being lower than the outer end thereof forming a pocket for the fuel. 70

5. In a vapor lamp, the combination with spaced burners, of a vaporizing tube located in a vertical plane that extends between the burners, said tube being formed with a serpentine curve that provides a plurality of substantially vertical loops disposed substantially in said plane and at different distances from the burner. 75

6. In a vapor lamp, the combination with spaced upstanding burners, of a vaporizing tube comprising an upstanding portion and another portion that is in the form of a serpentine curve, forming reversely arranged loops disposed one below the other between and at different distances from the burners, 80 the loops that extend in one direction being disposed lower than the loops extending in an opposite direction, and a mixing chamber associated with the vaporizing tube and connected to the burner. 85

7. In a vapor lamp, the combination with a mixing chamber and burner, of a vaporizing tube having a discharge end associated with the mixing chamber, a tip slidably fitted into the discharge end and having a central opening, and a supporting stem carrying the tip and engaged therewith at one side of the opening through said tip. 90 95

8. In a vapor lamp, the combination with a burner, of a mixing chamber connected thereto and having a dome at its top, said dome being provided with an inlet opening, a vaporizing tube associated with the burner and having a discharge end located above the opening, a tip slidably and snugly fitted in the discharge end and having a central tapered opening therethrough in alinement with the inlet opening of the dome, and a supporting stem for the tip secured to said tip and preventing the downward sliding 100 105 movement thereof. 110

9. In a vapor lamp, the combination with spaced burners, of a mixing chamber connected and located adjacent thereto, spaced air conduits located between the chamber and burners and terminating in a dome over the upper end of said chamber, said dome having a central opening therethrough, a vaporizing tube located between the burners and having a plurality of serpentine curves 115 arranged one below the other, said tube having a discharge end above the opening in the dome, a tip slidably fitted in the discharge end and having a secondary orifice therethrough, the inner portion of which is outwardly tapered, and a stem fixed to one side of the tip and constituting means for retaining said tip within the discharge end. 120 125

10. In a vapor lamp, the combination with a fuel conducting pipe, of a valve casing con- 130

- 5 nected thereto and having an off-set starting cup, said cup being provided with ears, a mixing and burner element secured to the ears and comprising spaced upstanding burners, and an upstanding mixing chamber communicating with the burners and located at one side of the same, said mixing chamber having exteriorly disposed air conduits communicating with its upper end and arranged 10 on the opposite side of the same, a vaporizing tube connected to the valve casing and extending upwardly in a vertical plane between the burners, portions of said tube being in the form of reversely disposed vertical loops, 15 the discharge end of the said tube being associated with the upper end of the mixing chamber, a tip located in the discharge end, a supporting stem for the tip, and a controlling valve located in the valve casing.
- 20 11. In a vapor lamp, the combination with the mixing and burner element comprising an upstanding mixing chamber and spaced upstanding burners, of a vaporizing tube located in a vertical plane at one side of the 25 mixing chamber and between the burners at different distances therefrom, said tube having a serpentine curve forming a series of vertical reversely disposed loops arranged one below the other.
- 30 12. In a vapor lamp, the combination with a burner, of a mixing chamber associated

therewith, a vaporizer tube having a discharge end associated with the mixing chamber, a tip detachably fitted in the discharge end of the vaporizer tube, said tip having a 35 tapered recess in its inner end and a discharge orifice through its outer end, said orifice being of less diameter than the recess and communicating therewith, and a stem secured to and constituting means for detachably supporting the tip in the tube. 40

13. In a vapor lamp, the combination with a burner, of a mixing chamber connected thereto and having a dome at its top, said dome being provided with an inlet opening, 45 a vaporizing tube associated with the burner and having a discharge end located over the opening, and a tip snugly fitted into the discharge end of the tube and having a central orifice therethrough that is aligned with the 50 inlet opening of the dome, said orifice having its inner portion outwardly tapered and its outer portion of less diameter than the tapered portion.

In testimony, that I claim the foregoing as 55 my own, I have hereto affixed my signature in the presence of two witnesses.

WILLIAM THOMAS WOOD.
